UNITED STATES PATENT OFFICE.

FREDERICK C. BALLSMITH, OF ATTICA, NEW YORK.

BUTTER CUTTER AND MARKER.

SPECIFICATION forming part of Letters Patent No. 230,392, dated July 27, 1880.

Application filed December 15, 1879.

To all whom it may concern:

Be it known that I, FREDERICK CHRISTIAN BALLSMITH, of Attica, in the county of Wyoming and State of New York, have invented 5 Improvements in Devices for Cutting and Stamping Butter, of which the following is a specification.

The object of this invention is to provide a device that will cut out pieces or shapes of 10 butter from crocks, tubs, firkins, or other large packages, and at the same time of cutting mark the surface of the butter in lines, grooves, or other designs, so as to present a handsome and uniform appearance for the table; and the invention 15 consists in a handle having two long cutting side pieces attached thereto, in the end of which is swiveled a knife or other cutting device. Above the knife, in between the side pieces, is set an adjustable roller, in which are 20 formed lines, grooves, or fanciful designs, all as hereinafter fully explained.

In the drawings, Figure 1 is a plan view, showing the whole device; Fig. 2, a side elevation with one of the side pieces removed.

25 A represents a wooden handle of sufficient length to be grasped by both hands. B B' are two metal side pieces attached to the base A' of the handle, which is flattened at the sides for this purpose. These two metal pieces are 30 flat and smooth on the outside, and inside are beveled down so as to give two cutting-edges, a a, the extreme ends being also beveled and sharpened. In these ends is arranged a knife or cutter, C, that loosely turns on its projecting end pivots, b b, set in holes or bearings in 35 the side pieces. The pivots of the knife are in a line with the cutting-edge, so that this edge will always be presented to the part of the butter to be cut, either if pressed downward, pulled toward the person using it, or drawn back or upward.

The knife is formed with a thick back that tapers to the cutting-edge.

It is obvious that a piece of wire set in place 45 of the knife and fastened to the sides would also operate to cut the butter; but I prefer the knife, as it thereby gives a sharp edge.

Above the knife, in said side pieces or frames

B, is set a roller, D, either plain, figured, or grooved, which acts also as a gage to determine 50 the thickness of the piece of butter to be cut; also, as it revolves over the surface of the butter while being cut, it stamps, marks, or impresses therein any figures cut in or on the roller, thereby giving each piece cut out a 55 handsome surface, and which may be repeated on the sides and back, if desired, by running the roller over them. Thus a handsome square or oblong piece of butter may be cut out of a mass, and without extra hand-work be ready 60 for use on the table, and, by the additional roller, made also ornamental in appearance.

It is usual to get butter out of tubs, &c., by digging it out in lumps with a knife, spoon, or stick, and put it on the table in such shapes, 65 or else it has to be worked over by hand to make it presentable. This device of mine will do away with any such work, and always cut out a piece in such shape as to be immediately presentable for the table.

To graduate the sizes of the pieces of butter to be cut out of a given size or weight, the roller D is set higher or lower in the frame B by the holes c c in the frames B B', the axle, pin, or pins d of the roller being removable 75 for that purpose.

I claim—

1. In combination with a handle, A, the two vertical metal knives B B', having double cutting-edges, and with a pivoted cutter, C, set 80 between the ends of the vertical knives in such a manner as to always present its cutting-edge, whichever way the implement is pushed or pulled, substantially as specified.

2. In combination with the handle A, side 85 pieces, B B', and knife C, the marking-roller D, all substantially as and for the purpose specified.

In witness whereof I have hereunto signed my name in the presence of two subscribing 90 witnesses.

FREDERICK C. BALLSMITH.
